CLAIM

The ornamental design for a molded surface of a concrete
product, as shown and described.

DESCRIPTION

FIG. 1 is a front view of a molded surface of a concrete
product;

FIG. 2 is a right side view of the surface depicted in FIG. 1;
FIG. 3 is a left side view of the surface depicted in FIG. 1;
FIG. 4 is a top view of the surface depicted in FIG. 1;
FIG. 5 is a bottom view of the surface depicted in FIG. 1; and,
FIG. 6 is a perspective view of the surface depicted in FIG. 1.
The broken lines in the drawing views are included for the
purpose of illustrating portions of the molded surface of a
concrete product that form no part of the claimed design.

1 Claim, 6 Drawing Sheets
